Primary Examiner — Antoine Duval Davis*(74) Attorney, Agent, or Firm* — Seager, Tufte & Wickhem, LLP(57) **CLAIM**

The ornamental design for an electric meter, as shown and described.

DESCRIPTION

FIG. 1 is a perspective view of an electric meter; FIG. 2 is a front view of the electric meter of FIG. 1; FIG. 3 is a left side view of the electric meter of FIG. 1; FIG. 4 is a right side view of the electric meter of FIG. 1; FIG. 5 is a top side view of the electric meter of FIG. 1; and, FIG. 6 is a bottom side view of the electric meter of FIG. 1. The broken lines in the drawings depict the environment for the claimed design and form no part of the claimed design.
